(57) **CLAIM**

The ornamental design for a self inflating mattress, as shown and described.

DESCRIPTION

FIG. 1 is a front view of the self inflating mattress in accordance with aspects of the present subject matter.

FIG. 2 is a top end view of the self inflating mattress illustrated in FIG. 1.

FIG. 3 is a cross-sectional right side view of the self inflating mattress illustrated in FIG. 1 taken along line 3—3; and, FIG. 4 is a perspective view of the self inflating mattress illustrated in FIG. 1.

The dash-dot broken lines contained within the figures, represent portions of the self inflating mattress that form no part of the claimed design.
